(57) **CLAIM**

The ornamental design for a baby bottle holder, as shown and described.

DESCRIPTION

FIG. 1 is a perspective view of a baby bottle holder, showing our new design, the broken line showing of the baby bottle being for illustrative purposes only and forming no part of the claimed design.

FIG. 2 is a left side elevational view of the baby bottle holder, the right side elevational being a mirror image of the left side view.

FIG. 3 is a front elevational view thereof.

FIG. 4 is a rear elevational view thereof.

FIG. 5 is a top plan view thereof; and,

FIG. 6 is a bottom plan view thereof.
